CAR DOOR LOCK

Wilfred A. Beauchamp, Chicago, Ill., assignor, by
mesne assignments, to The Youngstown Steel
Door Company, Cleveland, Ohio, a corporation
of Ohio

Application October 30, 1933, Serial No. 695,818

13 Claims. (Cl. 292—283)

This invention relates to car door locks and is directed primarily to locks for sliding car doors.

It is an object of this invention to provide locks for sliding car doors embodying hasp fasteners mounted for relative movement upon said doors.

A further object is to provide locks for sliding car doors embodying movable hasp fasteners capable of movement relative to the doors to take up any clearances in said locks and thus substantially decrease the wear on the parts thereof.

A further object is to provide locks for sliding car doors embodying hasp fasteners slidably mounted for relative movement upon said doors to take up clearances in said locks and means responsive to the relative movement between said fasteners and doors to maintain said locks in said condition.

A further object is to provide locks for sliding car doors embodying hasp fasteners mounted for sliding movement upon said doors and hasps swingably carried by said fasteners whereby said hasps may be engaged with staples secured to the car sides without the necessity of sledging said hasps to establish said engagement.

A further object is to provide locks for sliding car doors embodying hasp fasteners slidably mounted upon said doors whereby the tolerances between the parts of said locks may be materially reduced and the play between said parts decreased.

A further object is to provide locks for sliding car doors embodying hasp fasteners assembled with said doors for relative sliding movement and retainers secured to said doors in overlapping relationship with the hasp fasteners for maintaining said fasteners upon the doors, cooperating with downwardly tapered pins extending through and disposed in abutting relationship with the fasteners and retainers.

Other objects will become clear as the description of this invention proceeds.

In the drawings forming part of this specification:

Figure 1 is a fragmentary elevation of a railway car showing the invention applied thereto;

Figure 2 is a horizontal section taken on line 2—2 of Figure 1;

Figure 3 is a fragmentary elevation with part of the retaining member broken away to more clearly show the relationship of parts of the lock of the invention;

Figure 4 is a vertical section taken on line 4—4 of Figure 1;

Figure 5 is a vertical section taken on line 5—5 of Figure 1; and

Figure 6 is a vertical section taken on line 6—6 of Figure 1.

Referring to the drawings in which a preferred embodiment of the invention is illustrated, applicant's novel lock indicated as a whole by the reference numeral 10, is shown applied to a car door 11 adapted to slide relative to the side 12 of a railway house car in order to open and close a door opening 13 formed therein. The door opening is defined in part by means of a Z-shaped door post 14 provided with a wooden filler 15 as illustrated in Figure 2 of the drawings. The door post shown is disposed at the front edge of the door opening and carries an angle stop member 16 secured to the door post 14 by means of rivets 17 extending through one leg 18 of said stop member. The other leg 19 of said stop member cooperates with one flange 20 of the door post 14 to provide a recess adapted to receive the forward edge of the sliding door 11. The rivets 17 serve additionally to secure an angle member 21 to the door post 14, said angle member serving as a support for a lock plate 22 secured thereto by means of rivets 23. Said lock plate is provided with a staple 24 and carries a locking pin 25 adapted to extend through said staple. An aperture 26 is provided in the lower portion of said pin and in the operative position thereof is adapted to align with an aperture 27 provided in a flange 28 formed on the lock plate. A seal (not shown) is adapted to be extended through the aligned apertures.

As indicated above the door 11 is a sliding door and is adapted to be supported in the customary way by means of rollers or the like upon a supporting track for longitudinal movement relative to the car side. Inasmuch as the roller supports for said door and the track constitute no part of the instant invention these parts have been omitted from the drawings. The door illustrated preferably comprises a metallic panel 29 formed with a plurality of horizontally extending corrugations 30 which merge at their ends into vertical corrugations, one of which is indicated at 31. The vertical corrugation 31 is preferably reinforced by means of the channel reinforcing member 32. A reinforcing channel member 33 is secured to the front margin of the door and coacts with the angle stop member 18 to seal said margin of the door against the entrance of cinders and the like.

The lock means of the instant invention utilized to lock the door in its closed position is preferably mounted upon one of the horizontal corrugations 30 formed in the door panel 29. Said lock means comprises a retaining member 34

secured to the metallic panel 29 and provided with an outwardly offset housing portion 35 open at one end as indicated at 36. A hasp fastener 37 is slidably mounted upon the car door 11 5 and is disposed within the housing 35 formed on the retaining member whereby said hasp fastener is maintained upon the door. The fastener 37 is formed with an outwardly offset channel portion 38 intermediate the ends thereof and a neck 10 portion 39. The free end 40 of said neck portion extends through a reinforcing member 41 riveted to the hasp fastener by means of a plurality or rivets 42. As clearly indicated in Figure 2 of the drawings, the free end of the neck of the 15 hasp fastener may be upset so as to firmly fasten said end to the reinforcing member. The reinforcing member 41 shown in section in Figures 4 and 5 is provided with a plane face 43 lying in engagement with the hasp fastener 37 and a concave face 44 adapted to conform to the horizontal corrugation 30 upon which said fastener is mounted. The concave face of the reinforcing member 41, as clearly appears from Figures 2, 4 and 5 of the drawings, extends upon the opposite 20 sides of the crest of the corrugation 30 and lies in horizontal overlapping relationship with the vertical corrugation 31. In view of this relationship it will be readily apparent that the reinforcing member 41 is adapted to serve as a supplemental means to prevent disengagement of the 25 hasp fastener from the door.

The housing 35 formed on the retaining member 34 is provided with a vertically extending opening 45 through which a downwardly tapered pin 46 is adapted to extend. This pin, as clearly shown in Figure 2 of the drawings passes through the opening provided by the outwardly extending channel shaped portion 38 of the hasp fastener and the hasp fastener reinforcing member and 30 is adapted to be disposed with one side 47 thereof in abutment with flanges 48 and 49 provided on the retaining member 34. The opposite side 50 of said pin 46 which, as clearly shown in Figure 3 of the drawings, is tapered and is adapted to 35 abut a correspondingly tapered flange 51 provided on the relatively movable hasp fastener. Flanges 52 and 53 are provided upon the upper and lower extremities, respectively, of the tapered pin 46 and inasmuch as these flanges lie in overlapping 40 relationship with the hasp fastener and retaining member, as clearly shown in Figures 2, 4 and 5 of the drawings, it will be apparent that loss of said pin is avoided and that said pin serves to 45 prevent loss of the hasp fastener through the open end 36 of the retaining member.

In the assembly of applicant's lock the hasp fastener 37, the reinforcing member 41 therefor and the tapered pin 46 are disposed in the relationship clearly shown in Figure 2 of the drawings wherein the tapered pin lies in the space provided between the channel shaped offset portion 38 of the hasp fastener and the reinforcing member, and the hasp fastener and reinforcing member, subsequently, are riveted together by 50 means of the rivets 42. In view of the extent of the flanges 52 and 53 provided upon the extremities disengagement of the pin 46 from the hasp fastener and reinforcing member is prevented. It will be apparent, of course, before such assembly 55 takes place that a hasp 54 will be assembled with the neck 39 of the hasp fastener, said neck passing through an eye 55 provided in one extremity of the hasp. The free end of the neck 60 of the hasp fastener may then be upset as indicated at 40 so as to provide an additional fasten-

ing means between the hasp fastener and the reinforcing member. The unit provided by this assembly is then inserted into the retaining member 34 through the back thereof, which is left open for this purpose, and said retaining member with the hasp fastener assembly disposed therein is riveted to the door 11 as by means of rivets 56. The rivet 56 at the rear of the retaining member 34 passing through the corrugation 30 extends through a backing member 57 disposed upon the inside of the corrugation. It will be apparent after securing of applicant's locking member upon the door that the tapered pin 46 is adapted to abut the well 51 provided on the hasp fastener and the flanges 48 and 49 provided on the retaining member so that said hasp fastener cannot escape from the housing 35 of the retaining member. In the event, however, that the tapered pin 46 is broken and lost, escape of the hasp fastener will still be prevented because of the horizontally overlapping arrangement between the concave face 44 of the reinforcing member 41 and the vertical corrugation 31 provided in the door panel 29. It will be apparent, moreover, that in view of the downwardly tapered pin 46 and its disposition relative to the retaining member 34 and the movable hasp fastener 37, said hasp fastener is capable of horizontal sliding movement relative to the door and the retainer within the limits of the tapered pin.

The operation of the lock will be readily apparent in view of the foregoing description. When the door has been moved to its fully closed position as shown in Figure 2 of the drawings the hasp 54 is engaged with the staple 24 provided on the lock plate 22 and the pin 25 extended through the staple. A seal (not shown) may then be passed through the aligned openings 26 and 27 provided in the pin and in the flange 28 of the lock plate. The tapered pin 46 may then be lowered into abutting engagement with the walls 51 and flanges 48 and 49, and in this lowering movement of the pin the clearances between the hasp fastener and the hasp and between the hasp and the staple 24 of the lock plate will be absorbed, as clearly shown in Figure 2 of the drawings. It will be apparent, then, from this relationship of the door, the front stop angle 18 and the parts of the lock that no movement of the door toward open position can take place, either under impact upon the car to which the door is applied or because of jarring or vibration of the car during transit.

In the event that door has not been fully closed so as to establish the engagement between the front edge of the door and the front stop angle 18 as shown in Figure 2 of the drawings the lock may still function to fasten the door to the car and to take up all of the play or tolerance between the parts of the lock when the door assumes its full closed position. With the door partially open the hasp may readily be engaged with the staple on the lock plate by merely raising the tapered pin 46 so as to permit movement of the hasp fastener toward the lock plate. In view of this movement the hasp may readily be engaged with the staple 24 of the lock plate without the necessity of sledging said hasp over the staple as frequently occurs in practice with the locks now in use. In addition, it will be apparent that the tolerances between the hasp fastener and the hasp and between the hasp and the staple of the lock plate now required may be materially reduced. After the engagement of the hasp with the staple and the proper disposition

of the pin 25 with the lock plate the tapered pin 46 may be lowered so as to take up the tolerances between the hasp fastener and the hasp and between the hasp and the staple. When the door 5 subsequently assumes the full closed position shown in Figure 2 of the drawings said door may move relative to the hasp fastener. During this movement the tapered pin will automatically be lowered so as to maintain the tight engagement 10 between the hasp fastener, the hasp and the staple and the relationship of the parts will again be as illustrated in Figure 2 of the drawings. No subsequent movement between these parts can thereafter occur. However, if there should be 15 temporary binding engagement between the hasp fastener or its reinforcing member and the door so that, as the door moves to fully closed position, it will carry with it the hasp fastener and again introduce a tolerance or play between the hasp fastener and the hasp or between the hasp and the staple. It will be clear that the vibration 20 or jarring of the car in transit will tend to effect the lowering movement of the tapered pin 46 so that such tolerance or play will again be absorbed and the door will again assume the fully 25 closed position illustrated in Figure 2 of the drawings. When the door is to be opened after the car to which it is applied has reached its destination it is only necessary to elevate the pin 46, move the hasp fastener toward the lock plate 30 and readily release the hasp from the staple 24 of the lock plate. This release of the lock obtains even though the staple, through its engagement with the hasp, may be worn so as to form 35 a shoulder which, in the customary type of lock, makes it difficult to release the hasp fastener from the staple since the described movement of the hasp fastener will permit the disengagement of the hasp from the shoulder thus formed.

40 It will be apparent that numerous changes and modifications in the details of the invention will be clear to those skilled in the art. It is intended, therefore, that all such modifications and changes be comprehended within this invention, 45 which is to be limited only by the scope of the claims appended hereto.

I claim:

1. The combination with a relatively stationary member and a door slidable with respect thereto, of a lock for said door comprising a lock plate fastened to said relatively stationary member, a hasp fastener, a hasp carried by said fastener, a retaining member secured to said door for mounting said fastener for relative sliding movement upon said door and means for engaging said fastener and retaining member in the operative position of said lock for establishing automatically releasable fixed relationship therebetween, said hasp having operative engagement 55 with said lock plate in the operative position of said lock.
2. In a railway house car having a door opening and a slidable door for closing said opening, said door having an outwardly extending offset 60 adjacent a vertical margin thereof, a retaining member secured to said door, a hasp fastener disposed between said door and said retaining member in slidable relationship to said door and member and a hasp supported by said fastener, said fastener being provided with flanges positioned in horizontally overlapping relationship with said offset on said door whereby disengagement of said fastener from said door and retaining member by sliding movement is prevented.
3. In a lock for a sliding car door, in combi-

nation, a retaining member secured to said door, a portion of said member being offset relative to said door, a hasp fastener having a neck, said hasp fastener being positioned between said portion and said door, a reinforcing member secured 5 to said hasp fastener, the free end of said neck passing through said reinforcing member, said fastener and reinforcing member being slidable relative to said door and said retaining member and a hasp supported upon the neck of said fastener.

4. In a lock for a sliding door, a retaining member secured to said door, a housing provided on said member in offset relationship to said door, a hasp fastener lying in said housing in slidable 15 relationship to said member and said door, a reinforcing member secured to said fastener, said fastener having a neck portion extending through said reinforcing member and a portion offset relative to said reinforcing member, a pin lying in 20 said offset portion between said fastener and said reinforcing member, said pin extending through an opening provided in said housing and a hasp supported by the neck of said fastener.

5. In a lock for a sliding door, a retaining member 25 secured to said door, a housing provided on said member in offset relationship to said door, a hasp fastener lying in said housing in slidable relationship to said member and said door, a reinforcing member secured to said fastener, said fastener having a neck portion extending through said reinforcing member and a portion offset relative to said reinforcing member, a pin lying in 30 said offset portion between said fastener and said reinforcing member, said pin extending through an opening provided in said housing and a hasp supported by the neck of said fastener, said pin being flanged at its upper and lower extremities whereby said fastener, reinforcing member and pin may be assembled as a unit 35 prior to its disposition with the retaining member upon the door.

6. A lock for a sliding door comprising, in combination, a hasp fastener carrying a hasp, means secured to said door for mounting said fastener 45 for sliding movement upon said door, an abutment provided on said hasp fastener, an opposed abutment provided on said mounting means and a tapered pin disposed between said abutments for the purpose set forth.

7. The combination with a relatively stationary member and a door movable with respect thereto, of a lock plate fastened to said relatively stationary member, a hasp fastener, a hasp carried by said fastener, a retaining member secured to said door for mounting said fastener for relative sliding movement upon said door and means for releasably associating said fastener and said retaining member in fixed relationship, said hasp having operative engagement 55 with said lock plate in the operative position of said lock and said means comprising a tapered pin and abutments provided on said hasp fastener and said retaining member having engagement with said pin.

8. A lock for a sliding door comprising, in combination, a hasp fastener carrying a hasp, a reinforcing member secured to said fastener, said fastener having a substantially channel shaped portion offset from said reinforcing member, said 70 offset portion including a downwardly inclined side, a tapered pin disposed between said offset portion and said reinforcing member, means secured to said door for mounting said fastener for sliding movement upon said door, an abutment 75

provided on said mounting means, said pin being adapted to abut said inclined side and said abutment for the purpose set forth.

9. The combination with a relatively stationary member and a door movable with respect thereto, of a lock plate fastened to said relatively stationary member, a hasp fastener, a hasp carried by said fastener, a retaining member secured to said door for mounting said fastener for relative sliding movement upon said door and a pin having downwardly converging sides for releasably associating said fastener and said retaining member in fixed relationship, said hasp having operative engagement with said lock plate in the operative position of said lock.
10. The combination with a relatively stationary member and a door movable with respect thereto, of a lock plate fastened to said relatively stationary member, a hasp fastener, a hasp carried by said fastener, a retaining member secured to said door for mounting said fastener for relative sliding movement upon said door and means for releasably associating said fastener and said retaining member in fixed relationship, said means being capable of automatically reestablishing said fixed relationship when said relationship is broken, said hasp having operative engagement with said lock plate in the operative position of said lock.
11. The combination with a relatively stationary member and a door movable with respect thereto, of a fastening member for said door, means carried by said relatively stationary member for securing said fastening member thereto, means secured to said door for supporting said fastening member for relative sliding movement upon said door in the operative position of said fastening member and releasable means engageable with said supporting means

and said fastening member for initially establishing fixed relationship between said supporting means and said fastening member and for reestablishing fixed relationship upon relative sliding movement between said fastening member and said supporting means.

12. The combination with a relatively stationary member and a door movable with respect thereto, of a fastening member for said door, means carried by said relatively stationary member for securing said fastening member thereto, means secured to said door for supporting said fastening member for relative sliding movement upon said door in the operative position of said fastening member and a tapered pin engageable with said supporting means and said fastening member for initially establishing fixed relationship between said supporting means and said fastening member and for reestablishing fixed relationship upon relative sliding movement between said fastening member and said supporting means.

13. The combination with a relatively stationary member and a door movable with respect thereto, of a fastening member for said door, means carried by said relatively stationary member for securing said fastening member thereto, means secured to said door for supporting said fastening member for relative sliding movement upon said door in the operative position of said fastening member and a tapered pin engageable with said supporting means and said fastening member for establishing fixed relationship between said supporting means and said fastening member, said pin being biased downwardly for automatically reestablishing said fixed relationship when said relationship is broken.

WILFRED A. BEAUCHAMP.
